UNITED STATES PATENT OFFICE.

DORA E. MILLER, OF LOUISVILLE, KENTUCKY.

MATTRESS.

No. 928,778.

Specification of Letters Patent. Patented July 20, 1909.

Application filed April 2, 1907. Serial No. 365,988.

To all whom it may concern:

Be it known that I, DORA E. MILLER, a citizen of the United States, residing at Louisville, in the county of Jefferson and State of Kentucky, have invented new and useful Improvements in Mattresses, of which the following is a specification.

This invention relate to a bed mattress especially intended for invalids in which provision is made for receiving a bed pan or the like.

The invention has for one of its objects to improve and simplify the construction of a mattress of the character referred to so as to be comparatively easy and inexpensive to manufacture, extremely comfortable for the patient and adapted to permit the nurse to attend the patient with greater facility.

20 A further object of the invention is the provision of a mattress having a suitably arranged compartment that is open at one side for facilitating the placing and the removal of the bed pan or the like.

25 Another object is to provide a filler or removable section that is adapted to be normally contained in the compartment or chamber to complete the continuity of the mattress, the filler being readily removable when it is desired to position the bed pan.

30 With these objects and others in view, as will appear as the description proceeds, the invention comprises the various novel features of construction and arrangement of parts, which will be more fully described hereinafter and set forth with particularity in the appended claim.

35 In the accompanying drawings which illustrate one of the embodiments of the invention:—Figure 1 is a perspective view of the mattress. Fig. 2 is a sectional view of the receiving chamber or compartment showing the filler therein. Fig. 3 is a perspective view of the frame work around which the ticking of the mattress is placed to form the walls of the filler containing chamber or compartment. Fig. 4 is a perspective view of the filler.

40 Similar reference characters are employed to designate similar parts throughout the several views.

45 Referring to the drawings, 1 designates a mattress which may be of any approved construction, having adjacent one side and at the middle thereof, a compartment or chamber 2 that is permanently open at its top as

indicated at 3. The ticking or covering of the mattress is arranged to line this compartment, the ticking being attached to a skeleton frame 4, as shown in Fig. 3, the frame 60 being preferably of spring wire so as to give freely under the weight of the person resting on the bed. The compartment 2 is open at one side of the mattress and normally closed by a door 5 that is of any approved 65 construction and closed by a fastening 6. Adapted to fill the compartment 2 is a cushion or filler 7, which is filled with hair or other suitable material and covered with ticking, so as to match the mattress. The 70 ends of the filler or cushion have tabs or projections 8, to form hand holds whereby the cushion can be readily drawn out and handled. It will thus be seen that the filler preserves a smooth continuity of the mattress so that the bed will be comfortable to the patient and enables the mattress to be used for ordinary purposes, while provided with emergency means so that it is well adapted for invalids.

75 In practice the parts of the mattress are arranged, as shown in Fig. 1, and when occasion requires, the door 5 is opened and the filler 7 is removed, so as to form a compartment into which a bed pan or the like, 80 can be placed. This manner of attending to patients is extremely convenient and less laborious to the nurse or attendant, and insures greatest possible comfort to the patient.

85 From the foregoing description taken in connection with the accompanying drawing, the advantages of the construction and method of operation will be readily apparent to those skilled in the art to which the invention appertains and while I have described the principle of operation of the invention together with the device which I now consider to be the best embodiment thereof, I desire to have it understood that the device shown is merely illustrative and 90 that such changes may be made when desired as are within the scope of the claim.

95 What is claimed, is:—

100 A mattress comprising a casing and a filling therefor, said casing being constructed 105 with a compartment adjacent the middle of the mattress and at one side thereof, said compartment extending from the top to the bottom of the mattress and being closed at its bottom and three sides and having an opening 110 in the side of the mattress and one in the top thereof; a filler for the compartment and

comprising a casing, a frame therein to give form to the filler and filling material in the casing, said filler being removable through the side opening of the said compartment and being of larger area than the top opening for preventing displacement of the filler therethrough; a door hingedly connected with the side of the mattress arranged to

cover the side opening thereof; and a device for fastening the door in closed position. 10

In testimony whereof, I affix my signature in presence of two witnesses.

DORA E. MILLER.
